RICHARD F. SCHULZKE AND DELBERT L. HAMILTON, OF PORTLAND, OREGON

NECKTIE PRESS

Application filed October 1, 1928. Serial No. 309,371.

This invention relates to improvements in tie presses.

The primary object of this invention is the provision of an adjustable tie press or tree comprising relatively movable divergent side members with improved means to wedge the same into pressing relation within the pocket of a tie, to press wrinkles and creases from the tie or cravat.

10 Other objects and advantages of this invention will be apparent during the course of the following detailed description.

In the accompanying drawings, forming a part of this specification, and wherein similar reference characters designate corresponding parts throughout the several views,

Figure 1 is a front elevation of the improved tie press.

Figure 2 is a sectional view taken longitudinally through the tie press in the plane thereof.

Figure 3 is a cross sectional view taken substantially on the line 3—3 of Figure 2.

Figure 4 is a perspective view of a crown piece used to hold the tie press parts in assembled adjustable relation.

In the drawings, wherein for the purpose of illustration is shown only a preferred embodiment of the invention, the letter A may 30 generally designate the tie press or tree, which comprises pressing arms B and C pivotally held in assembled relation by a crown piece D; means E being provided for wedging the pressing arms B and C into tie pressing relation.

In tie presses which have heretofore been provided, either the members which do the pressing are connected together in such a bulky way as to leave rivets, or other projections which catch in the material of the tie as the tie press is being inserted into the tie pockets, or instead of pressing the tie into proper form, the material is either damaged or the bulky parts leave their imprint in the tie after it has become partially pressed. With this in mind the improved tie press is not provided with any projecting shanks, rivet heads, or the like, but fits in an efficient relation within the tie; having novel and improved wedge means for firmly press-

ing the tie in a proper relation, according to the shape of the tie.

The pressing arms B and C are of elongated formation, channel-shaped in cross section, each of the same comprising the side 55 walls 10 and 11 connected by the arcuated portion 12 which forms the convex pressing edge adapted to engage against the inside marginal edge of the tie during pressing. The walls 10 and 11 are of course parallel, 60 and provide a channel groove 13 wherein the wedge device E cooperates in an adjustable relation. The walls 10 and 11 are not very wide, but preferably diverge or taper upwardly from their lower ends to the crown 65 piece D.

The crown piece D, as is shown in Figure 4 of the drawings, comprises a substantially flat segmental head 25, having a rounded convex margin 26 which enables the insertion of 70 the press into the tie without damage to the material thereof. A reduced flat attaching shank 28 is rigid or integral with the head portion 25, and it is provided with openings 29 transversely therethrough.

The arms B and C are pivotally assembled upon the crown piece D by insertion of the shank 28 into the upper ends of the channel grooves of the arms B and C; countersunk head rivets 35 being provided for riveting 80 the walls 10 and 11 of the arms B and C through the openings 29 of the shank 28. Since the shank 28 is reduced, the outer surfaces of the walls and connecting portions 10, 11 and 12 of the arms B and C lie flush 85 with the outer surfaces of the head 25, to insure that no part of the tie press will catch in the material of the tie as the tie press is being inserted into the pocket of the tie, and which will be apparent from the drawings.

90 The wedge means E is reciprocable along the arms B and C, operating within the plane in which said arms lie, in the channel grooves thereof, and in such relation that the movement thereof relative along the arms B and C will not interfere with the material of the tie; the wedge means E having handle means which is adapted to extend from the larger open end of the tie for operating in its wedge 95 100

action to properly adjust the pressing arms within the tie pocket.

More specifically, the wedge means E preferably consists of wedge strips or pieces 50 and 51, respectively slidable along the grooves 30 of the channel shaped arms B and C. These strips 50 and 51 are snugly slidable within their respective channels, and they are elongated, having the ends thereof convex, 10 and in width they are less than the depth of the slots 30 in which they ride. The pieces or strips 50 and 51 are each provided with facing concavities 53, within which the laterally extending segmental projections 54, 15 forming part of the head 55 of the slidable operating member 56, seat. The operating member 56 includes a flat body 57, which is recessed longitudinally at 58 to lessen the weight thereof, and which is provided with 20 the upper reduced shank 59 upon which the head 55 above described is formed. The body 57, the shank 59 and the head 55 are all integral and are flat, of the same thickness, and slidably cooperate longitudinally in the 25 slots of the channel arms B and C. The opening 58 provides a handle 60, so to speak, which extends beyond the non-pivoted ends of the arms B and C, which an operator may grasp to operate the wedge structure E longitudinally in the arms B and C and bring the latter into a pressing relation with the tie material.

In order to guide the arms B and C, and to prevent detachment of the parts of the 35 wedge apparatus E from the arms B and C, it is preferred to provide preferably straight elongated slots 65 and 66 in the body 57 of the operating piece 56; said slots 65 and 66 being at opposite sides of the opening 58 and 40 converging from the handle end 60 of the member 56, at a uniform slope at opposite sides of the longitudinal axis of the member 56. In the lower ends of the arms B and C, that is, opposite their pivoted ends on the 45 member D, the walls 10 and 11 of the arms B and C are each provided with guide pins or rivets 68, having counter-sunk headed attachment in the walls 10 and 11, so that the pins 68 extend across the grooves of the arms 50 B and C, for seating in the slots 65 and 66 of the operating member 56, as shown in Figures 1 and 2 of the drawings.

In operation, the member 56 is pulled downwardly, or counter to the crown piece D; and 55 this permits a collapsing of the arms B and C, either incident to the operator pressing the arms B and C together, or the cam action of the pins 68 in the slots 65 and 66. The arms B and C having been collapsed to the desired 60 extent, the device is inserted with its crown piece D foremost into the pocket of the tie; the plane of the parts of the improved pressing device A lying of course in the plane of the pocket of the tie. The device is inserted 65 to the desired extent into the pocket of the

tie, and the member 56 is then moved upwardly relative in the channels of the arms B and C, by the operator pressing on the handle end of the member 56. Inasmuch as the convex lugs 54 fulcrum in the recesses of the wedge shoes 50 and 51, the latter will be slid upwardly into the grooved slots of the channel pieces or arms B and C, spreading the latter apart, that is, swinging them on the pivot pins 35, and moving the convex edges 12 thereof into engagement against the side edges of the tie which is to be pressed. The wedging action of the apparatus or means E is thus accomplished to the desired extent, until the wrinkles are effaced from the tie, and incident to the frictional connection of the shoes 50 and 51 in the channel pieces B and C, the apparatus E will hold its wedge engagement in the arms B and C to hold the latter arms tightly pressed in a stretching relation upon the tie which is received thereover. It is to be noted that the strips 50 and 51 will fulcrum accurately upon the lug ends 54 of the operating slide 56, as can readily be seen from Figures 2 and 3 of the drawing. The pressing action as accomplished by the clamping means E is not accomplished by the slide of the pins 68 along the slots 65 and 66, that is, there is no cam action during the inserting movement of the wedge means E along the arms B and C toward the crown piece D; the shoes 50 and 51, accomplishing the wedge action, with sufficient friction to hold the pressing position.

Various changes in the shape, size, and arrangement of parts may be made to the form of invention herein shown and described, without departing from the spirit of the invention or the scope of the claims.

We claim:

1. In a necktie press of the class described 105 the combination of elongated straight pressing arms of substantially channel shaped formation, means pivotally connecting the arms together at similar ends with the arms extending divergent away therefrom and the channels facing each other, elongated slide pieces in said channels, an elongated operating handle, means fulcruming the operating handle to said slide pieces, said operating handle having elongated slots therein for each 110 of the pressing arms, and pins at the free ends of said pressing arms operating in said slots to guide the relation of the operating handle in its movement with respect to the pressing arms.

2. In a necktie press the combination of 115 pivotally connected divergent pressing arms; a wedging slide longitudinally movable between the pressing arms towards or away from the pivot connection of the arms, and means positively camming the slide to each of 120 said pressing arms for both positive regulated opening and closing movements of the pressing arms as the slide is moved respectively.

5 towards and away from the pivots of said arms.

6 3. In a necktie press the combination of
7 elongated pressing arms, means pivotally con-
8 necting them together at similar ends, an
9 elongated wedge device slidable between said
10 arms and operable from the free ends of the
11 arms for such sliding, and pin and slot con-
12 nections camming each of said arms to said
13 wedge device for a relative opening and clos-
14 ing movement upon moving the wedge device
15 relatively back and forth between and along
16 said arms.

17 4. In a necktie press the combination of
18 elongated pressing arms, an elongated wedge
19 member operating between said arms, said
20 wedge member having a pair of relative con-
21 verging slots longitudinally therein, and pins
22 connected with said arms operating in the
23 slots connecting one of the arms slidably to
24 one slot and the other arm slidably to the
25 other slot whereby upon relative movement
of the wedge member longitudinally between
the arms the latter will be laterally expanded
and contracted.
